THERMOSTATIC ELECTRIC-CIRCUIT CONTROLLER.

Application filed April 13, 1920. Serial No. 373,557.

To all whom it may concern:

Be it known that I, ALLEN E. CHISHOLM, a citizen of the United States, and a resident of Portland, county of Multnomah, State of Oregon, have invented a new and useful Improvement in Thermostatic Electric-Circuit Controllers, of which the following is a specification.

My invention relates to means for effecting the thermostatic control of an electric circuit so as to make or break such circuit in the presence of a predetermined temperature.

The purpose of my invention briefly stated is this: The movement of a thermostatic element per degree of change in temperature is only slight, and if such movement alone be depended on for causing the break or make in an electric circuit, serious consequences may ensue. In short, there is a critical period just at the instant of making or breaking the circuit, and if the action of the means effecting such make or break be not rapid enough, there is a tendency of causing an arc between the electrical contacts during the operation of the make-and-break.

With circuits of low voltage and small amperage, such arcing may be but slight, nevertheless it will eventually so roughen the contacts that they become unreliable for further service; and in circuits of greater amperage and moderate voltage, the arcing may be so severe as to cause the contacts to be melted or welded together.

Hence, a thermostatic control for a make or break in which one contact of the circuit is carried by a thermostatically positioned member and depends on the motion of said latter member for making or breaking the circuit will not answer the purpose as above outlined.

The object of my invention is to provide thermostatically operated means which will effect the make or break of the circuit so instantaneously as to prevent the forming of an arc between said electrical contacts.

I attain my object in the combination with the make-and-break of an electric circuit, of mechanical means—preferably spring controlled—whereby said make-and-break is operated with great rapidity, and thermostatic means by which said mechanical means are thrown into action.

I will describe the practical use of my invention in connection with an electrically

heated sad-iron, also with regard to an automatic electric fire alarm.

Describing first the use of my invention on an electric iron: Experience has taught that an electric iron will become heated to a dangerous degree if the current is left on while the iron is not in use. While ironing, the excessive heat of the iron is dissipated by the damp clothes; but when the iron is permitted to stand with the current on, its temperature will rise rapidly to the dangerous point; and if the iron rests on an inflammable surface it may ignite the latter; or even if such be not the case, the excessive heat will tend to damage, or probably destroy the heating element of the iron.

The object of any automatic thermostatic control for electric irons is of course to break the circuit before the danger point is reached; but for such controlling means to be maintained in a dependable state the devices must be adapted to effect the interruption of the circuit instantly, in the presence of the predetermined maximum degree of heat.

Furthermore, in an electric iron, two essential features are required to insure safety.

First: The devices must be so arranged that when once the circuit is interrupted by the presence of the predetermined excessive degree of heat, the electric circuit will not become automatically re-established, with the mere drop in temperature below the predetermined maximum degree; but, to the contrary, the devices must be so arranged that some manual action on the part of the operator is required for re-establishing the circuit; for, if the devices are so arranged as to cause the automatic re-establishment of the circuit upon a mere drop in temperature, then the iron would be maintained at a temperature close to the danger point, and if forgotten and neglected, a fire may result.

Secondly: The device should be so arranged that when once the current is interrupted because of an excessive degree of heat having been attained by the iron, the circuit cannot be re-established by any manual adjustment of the devices until the temperature has again fallen below the predetermined maximum degree of heat; otherwise, the function of the automatic control would be practically nullified.

Describing next the use of my invention in a fire alarm system: It is well known that on lines that are normally open and which

lates, and said lines are at all times more or less heavily charged with this static current.
5 Hence, when a conductor of opposite polarity is brought near this statically charged line, the static electricity is discharged as soon as the dielectric strength of the surrounding air is less than the static potential 70
10 of the line, and if, for example the line be carrying direct current with a normal line voltage of 100 volts or more, and the air gap be gradually diminished, as with the average thermostatic controlling device, then a
15 condition may arise whereby the static discharge will start an arc which will be maintained by the normal line voltage.

Furthermore, even if an arc is not maintained, the static discharges will eventually 20 roughen the contact points; therefore, as obvious it is necessary that the make and break should be instantaneous in its operations.

In Sheet 1 of the accompanying drawings, I have shown my device as used in 25 connection with an electric sad iron, namely,

Fig. 1 is a plan view of an electrically heated iron embodying my invention, the cover or housing and handle of the iron being 30 removed;

Fig. 2 is a transverse section of Fig. 1, on the line 2-2;

Fig. 3 is a front elevation of the interior devices of the iron, the housing or cover and 35 the handle being shown in section;

Fig. 4 is a perspective view of the device combined in my invention with parts broken away to disclose parts which otherwise would be covered;

Fig. 5 is a perspective inverted sectional detail of the adjustable latch hooks included in my invention;

In Figs. 6 to 9 inclusive I have illustrated the practical application of my invention 45 to an electric fire-alarm system; thus, Fig. 6 is an elevation of an electrical alarm device embodying my invention, the electric circuit being indicated by diagram;

Fig. 7 is a plan view as seen with the 50 housing *z* removed from its support;

Fig. 8 is a transverse section on the line 8-8 of Fig. 7; and

Fig. 9 is a perspective view of certain 55 parts of the mechanism embodying my invention.

The general construction and operation of my device as shown in Figs. 1 to 5 inclusive illustrating, as mentioned the use of my invention in an electrically heated 60 sad iron are as follows:

a and *a'* are complementary members of the thermostat element which comprises two members *a*, *a'* each composed of two strips of metal, for example, of unequal co-efficients of expansion. The strips of which 65

then rigidly fastened together, preferably by riveting. The thermostat members *a*, *a'* are then combined in the form of a full elliptic spring, the extremities of said members being hinged together as at *a*².

By providing a thermostat element constructed as shown, that is to say, in the form of a full elliptic spring comprising two members as *a*, and *a'*, an appreciably greater movement is obtained than if a thermostatic element were employed comprising only one member like *a* or *a'*.

The thermostat member *a* is firmly mounted in slots provided in supporting posts *c* between insulating mica plates *b*; the posts *c* being affixed on the base plate *d*.

In the design shown in Figs. 1 to 5 inclusive, the metal of the least co-efficient of expansion, is placed on the outer or longest side of the curved thermostat members. Hence, under the action of heat, the greater coefficient of expansion of the metal comprising the inner leaves of the thermostat 90 members *a* and *a'* will tend to flatten the ellipse, and thus shorten the transverse axis which gives the mechanical movement desired.

A latch-bar *e* provided with hinge ears 95 at one end is hinged to a hinge plate *g* by a hinge-pin *f*; the hinge member *g* being riveted to the thermostat member *a*.

The opposite end of the latch-bar *e* has a perpendicular portion *e'* which carries an 100 adjustable latch-hook *k*, the latter being fastened to said latch bar by an adjusting screw *j*, as more clearly shown in Figs. 2 and 5. An insulated button *s*, on the latch bar *e*, projects up thru a hole in the cover 105 3. The button *s* is secured to the hook *k* by a screw *s'*, and the latter bears in a slot *s*².

A spring *h* is riveted to the hinge-plate *g*, and the free end of this spring bears under 110 tension, against the underside of said latch bar, normally lifting the latter and thus breaking or opening the circuit as will be seen.

n is a metallic plate contact-member, fixed 115 in place on the base plate *d* between insulating mica plates *p*, *p'* by a screw *o*, which threads into the base plate *d*.

l is a brass spring riveted at its fixed end 120 to the latch bar *e*, and provided at its free end with a non-corrosive tip *m*.

The latter constitutes one of the electrical contacts of the make-and-break of my device, and the plate *n* has a stepped portion *n'* 125 which constitutes the other electrical contact member.

A latch hook *i* is rigidly fastened on the thermostat member *a'* and the parts are so arranged that in temperatures under a predetermined maximum degree the latch-hook 130

connection of the heating element of the
5 sad iron with the thermostat member *a*,
to which one end of said arm *w* is fastened
by a stud screw *r*.

x is a bar constituting an electrical con-
nection between the source of electric energy
10 and the electrical contact member *n* to which
it is fastened by stud-screw *q*.

y is an electrical connection between the
heating element of the iron, and the source
15 of electric energy thru a member *u*.

15 *t*, *t* are two studs firmly supported on
the base plate *d*. On the studs *t*, *t* are
threaded nuts *t'* for fastening the housing
3 and handle 4 in place.

The operation of the parts thus far de-
20 scribed is as follows:

So long as the iron remains below the
predetermined maximum temperature, elec-
tric current may flow from the service line
25 to bar *x*, thence thru plate *n* to contact *m*,
thence thru spring contact-finger *l* to latch-
bar *e*, thence thru hinge-ear *g*, to thermo-
stat member *a*, thence thru stud *r*, to arm *w*,
thence to heating element, thru the latter
30 to arm *y*, and thence back to service line.

30 Contact is maintained between the con-
tact members *m* and *n*, thru the medium
of the latch-bar *e*, which is held in the
position shown against the tension of spring
35 *h*, by restraining devices, that is to say,
thru the engagement of latch-hook *k*, car-
ried by the latch bar *e*, with latch-hook *i*.

Under normal heat conditions, the ther-
mostatic action will be insufficient to cause
40 the parts to function so as to open the cir-
cuit. As soon, however, as the temperature
exceeds the predetermined degree, the move-
ment of the thermostat element will be such
as to cause the latch hook *i*, to disengage
45 from latch hook *k* of the latch-bar *e*.

45 The tension of the spring *h* will then
instantly throw the latch lever *e* up there-
by instantly separating the contacts *m* and
n, and breaking the electric circuit.

50 After this action has taken place, the elec-
tric circuit cannot be re-established and
maintained until the temperature has
dropped to such extent as to re-adjust the
thermostat so that latch hook *k* may again
55 be engaged with the latch hook *i*.

55 When sufficient cooling has taken place,
the insulated button *s* may be pressed down
thereby causing the latch hooks *k* and *i* to
become re-engaged, thus re-establishing the
60 electrical connections and maintaining the
same until temperature again becomes ex-
cessive. Should the operator forget to shut
off the current when thru using the sad iron,
the circuit will be automatically opened as
65 soon as the high temperature is reached and
the danger of over-heating will be obviated.

thru the device. Hence the operation of
the thermostatic means to effect a break in
70 the circuit is due to a rise in temperature
above a predetermined degree resulting from
the heat acquired by the device while being
supplied by the normal current in a normal
way. If the work done with the iron dis-
75 pates the heat radiated by the latter to such
extent as to keep this heat below a predeter-
mined temperature, nothing will happen;
but if the degree of heat acquired by the
iron runs above said temperature the latch
80 holding the make-and-break in its circuit
making position will be released, and the
latch cannot then again be readjusted to its
holding positions until the temperature is
85 reduced.

Therefore, the statement in some of the
claims, that the thermostatic means are
adapted to render said latch holding means
90 inoperative by the passing therethru of the
normal electric current thru the normal cir-
cuit. It is to be understood that there is to
be no manual change or adjustment effected
in the operation of the device, so as to alter
95 the relationship of the current passed thru
the device and resistance element carried by
the latter.

Referring now to Figs. 6 to 9 inclusive, I
have shown my thermostat as applied to a
fire-alarm system. In this application, the
100 parts shown which correspond with similar
parts in Figs. 1 to 5 are given the same ref-
erence letters.

In the design of thermostat shown in Figs.
6 to 9 inclusive, the disposition of metals is
105 reversed from that shown in Figs. 1 to 5 in-
clusive, in order that the short axis of the
ellipse will increase under action of heat.

The pins *c*, *c* extend thru the frame *d'*, and
are provided with nuts *s'* and lock nuts *t'*.
The cover *z* is held in place by the lock nuts
110 *t'*, and a seal *t'* prevents unauthorized re-
moval of the cover.

A nut *o'* engages the stud *o*, and the con-
tact tip member *m* is omitted. It is to be
115 noted that the base-plate *d* is extended so as
to permit the thermostat to be conveniently
fastened to the ceiling, and the electrical
connections 3 and 4 connect directly with the
studs *q* and *r* respectively.

Batteries 5, 6 provide a source of current
120 for energizing the circuit. 7 is an alarm
gong, 8 is a solenoid switch, and 9 is a drop
annunciator which indicates the location of
the fire.

In the event of a fire, the heat will cause
125 an expansion of the thermostat which will
release the engagement between latch hook
i, and latch hook *k*. The spring *h'* will then
rock the lever *e* so as to cause the member *l*
130 to make electrical contact with the member

as follows:

Energizing of the solenoid switch will close the circuit of the gong 7, causing it to operate and thus give the alarm.

- Simultaneously, the annunciator will function so as to drop the indicator and thus point out the location of the fire.
- 10 It is obvious that my device may be used in various other ways than those described above, but the description given is sufficient to point out fully those features which characterize my invention.

15 I claim:

1. In an electric circuit provided with a make-and-break element, the combination with the latter of a thermostatic element comprising two members arranged like a full elliptic spring, one of said members being fixed in place, a movable member carried by said fixed member of said thermostatic element, one contact in said make and break carried by said movable member, the other contact of said make and break being relatively fixed in place, spring actuated means for throwing said movable member into its position for opening the circuit, and devices for holding said movable member in its position for closing said circuit, said thermostatic element being adapted at a given temperature to release said movable member from said devices.
2. In an electric circuit provided with a make-and-break element, the combination with the latter of a thermostatic element, comprising two members arranged like a full elliptic spring, one of said members being fixed in place, a movable member carried by said fixed member of said thermostatic element, one contact in said make and break actuated by said movable member, the other contact of said make and break being relatively fixed in place, spring actuated means for throwing said movable member into its position for opening the circuit, and devices for holding said movable member in its position for closing said circuit, said thermostatic element being adapted at a given temperature to release said movable member from said devices.
- 45 3. In an electric circuit provided with a make-and-break element, the combination with the latter of a thermostatic element comprising two members arranged like a full elliptic spring, one of said members

element, one contact of said make and break being actuated by said movable member, the other contact of said make and break being relatively fixed in place, spring actuated means for throwing said movable member into one position relative to the closing of the circuit, and devices for holding said movable member in position for closing the circuit, said thermostatic element being adapted to release said member at a given temperature, thereby closing the circuit.

4. The combination of an electric circuit provided with a make-and-break element, a thermostatic element comprising two members arranged like a full elliptic spring one of said members being fixed in place, a movable piece carried by one member of said thermostatic element, one contact in said make and break carried by said movable piece, the other contact of said make and break being relatively fixed in place, automatic means for throwing said movable piece into its position for opening said circuit, and devices for holding said movable piece in its position for closing said circuit, said thermostatic element being adapted at a given abnormal temperature to release said movable member from said holding devices and thereby rendering the latter inoperative during the continuance of said abnormal temperature.

5. The combination of an electric circuit provided with a make-and-break element, a thermostatic element comprising two members arranged like a full elliptic spring one of said members being fixed in place, a movable piece carried by one member of said thermostatic element, one contact in said make and break carried by said movable piece, the other contact of said make and break being relatively fixed in place, spring actuated means for throwing said movable piece into its position for opening said circuit, and devices for holding said movable piece in its position for closing said circuit, said thermostatic element being adapted at a given abnormal temperature to release said movable member from said holding devices and thereby rendering the latter inoperative during the continuance of said abnormal temperature.

ALLEN E. CHISHOLM.
